UNITED STATES PATENT OFFICE.

HARRY W. THOMSON AND WILLIAM F. WINKELMANN, OF JEFFERSON CITY, MISSOURI.
ASSIGNORS TO HOUSEHOLD APPLIANCE COMPANY, OF JEFFERSON CITY, MISSOURI,
A CORPORATION OF MISSOURI.

FLUID-DISCHARGING DEVICE.

Application filed October 19, 1921. Serial No. 508,700.

To all whom it may concern:

Be it known that we, HARRY W. THOMSON and WILLIAM F. WINKELMANN, citizens of the United States, and residents of Jefferson City, in the county of Cole and State of Missouri, have invented a new and useful Improvement in Fluid-Discharging Devices, of which the following is a specification.

10 This invention relates to fluid discharging devices particularly adapted for washing dishes and is an improvement on the general type of dish washing device shown in Carter Patent, No. 1,328,942, patented Jan. 27, 1920, wherein a soap container, comprising a foraminous cylindrical shell having an imperforate bottom and a perforated cover having radial vanes thereon, is rotatably supported within a casing 15 adapted to receive water from a faucet and discharge it as a soapy mixture.

One of the principal objects of the present invention is to provide for a more direct passage of the water through the soap container, whereby a more soapy mixture is produced. Another object is to protect the hands of the operator from the heat of the water passing through the device. Another object is to provide a removable self-centering pivot-support for the soap container. Another object is to provide for the ready attachment of the flexible connecting tube to faucets of different sizes and shapes. Another object is to secure a water-tight 20 lock-joint between the cap and nozzle members of the device. Other objects are simplicity of construction, reduced cost of manufacture and increased efficiency.

The invention consists in an improved 25 soap container, in the improved pivot-support for said container, in means for insulating the handle portion of the device, in means for attaching the flexible connecting tube to various existing types of faucets, in means for securing a water-tight joint 30 between the nozzle and cap members of said device; and it further consists in combinations and arrangements of parts hereinafter described and claimed.

In the accompanying drawing, which forms part of this specification, and wherein like symbols refer to like parts wherever they occur,

Fig. 1 is a side elevation of our improved dish-washing device provided with means 55 for detachably securing the connecting tube to an ordinary house faucet;

Fig. 2 is an enlarged central longitudinal section through said device on the line 2—2 in Fig. 1;

Fig. 3 is a plan view of the nozzle member of the casing, showing the soap container mounted therein;

Fig. 4 is a similar view of said member, the soap container being removed to disclose the pivot-support therefor;

Fig. 5 is a side elevation of the soap container;

Fig. 6 is a perspective view of the pivot-support therefor; and

Figs. 7, 8 and 9 are an end view, a longitudinal section and a side elevation, respectively, of the inlet end of the flexible connecting tube, illustrating in detail the means for securing said end to the faucet. 75

In the accompanying drawing, our dish-washer is shown in the form of a tubular casing A comprising a nozzle member 10 and a cap member 11 having an enlarged portion 11^a adapted to fit over the open 80 end of said nozzle member. The enlarged base portion 11^a of the cap member 11 forms an annular shoulder 11^b that overhangs the upper end of the nozzle member 10; and disposed between said shoulder and 85 said end is an annular gasket member 11^c, preferably of india-rubber or other elastic substance. The nozzle member and cap member are preferably locked together against accidental separation by means of oppositely disposed bayonet-joints comprising cooperating projections 12 and L-shaped 90 grooves 13 formed on the contacting portions of said nozzle member and said cap, respectively, the transversely extending portions of the grooves being inclined upwardly. By this arrangement, the nozzle member can be readily secured to the cap by a simple pushing and turning movement of the projections 12 in the grooves 13, the inclined portions of said grooves causing the upper edge of the nozzle member to be forced against the elastic gasket, thereby 95 preventing leakage between the cap and nozzle members of the casing.

Extending upwardly from the cap mem-

ber 11 is an axially projecting inlet tube 14 adapted to fit into one end of a flexible tube 15, which is preferably held thereon by cementing. The opposite end of the tube 15 is adapted to be attached to an ordinary house faucet 16 in a manner hereinafter described. The lower end of the nozzle member has a tapered nose portion 17 which is provided at its end with a plurality of discharge ports or spray orifices 18 after the manner of a rose-head.

Located within the lower portion of the nozzle member is a supporting member B comprising a wedge shaped plate 19, which is arranged with its apex down to fit the tapering nose portion of said nozzle member and has a rectangularly shaped integral cross-head 20 spaced above the upper edge or base of the triangle, said cross-head being twisted to a position at right angles to said triangular plate portion. The cross-head 20 and the base line of the triangular plate 19 are of a length corresponding to the inside diameter of the upper portion of the nozzle member 10, thus preventing bodily movement of the supporting member in directions transverse to the axis of the casing. The cross-head 20 is provided, at its upper edge, with a bearing portion in the form of a semi-circular projection 21 located midway between the ends thereof and in line with the longitudinal axis of the casing.

Rotatably supported within the upper portion of the nozzle member 10 on the bearing portion 21 of the supporting member 13 is a foraminous soap container C comprising a perforated cylindrical shell 22 having an imperforate bottom provided with a central depression 23 adapted to fit the bearing portion 21 of said supporting member. The container is provided with a cone-shaped cap or cover 24 having a cylindrical base flange which fits over the upper edge of the cover 24 is disposed opposite to the inlet in the casing; and said cap is provided with a plurality of elongated slots 25 disposed transversely to the axis of the container and at right angles to each other. The metal resulting from the punching of these slots is bent upwardly along the outside margin thereof in the form of upstanding flanges 24. With this arrangement, water upon entering the casing strikes the flanges 26, which constitute vanes, and the impact of the water thereon causes the soap container C to rotate upon the pivot-bearing 21 provided therefor on the supporting member B. The water upon striking the cover 24 for the soap container also passes through the openings 25 into the soap container, causing the soap therein to be commingled with the water passing therethrough. The resulting soapy mixture thence passes through the perforations in the wall of the container

into the nose portion of the casing and is discharged through the spray orifices 18 thereof onto the articles to be washed.

The flexible tube 15 is provided at its inlet end with a thimble 27 for readily attaching said end of said pipe to faucets of various types. Said thimble comprises a cylindrical sleeve provided at one end with an annular flange 28. The thimble is sleeved on the flexible tube 15 and has a flared portion 29 which forms a conical seat or shoulder adapted to bear against a bead 30 formed on the inlet end of said tube. One end of a chain 31 is secured to the annular flange 28 of the thimble 27, and the other free end portion of said chain is adapted to be inserted laterally into a notch 32 formed in the opposite side of said annular flange. The tube may be securely attached to the faucet 16 by forcing the inlet end of said tube over the end of the faucet. The free end of the chain is then looped around the valve portion of the faucet, then drawn tight, and then inserted sideways into the notch 32 in the thimble 27, lengthwise movement of the chain through the slot being prevented by the enlarged return-bends of the links. The action of pulling the chain tightly about the faucet draws the thimble 27 against the beaded portion 30 of the tube and prevents the tube from being forced off the faucet by the pressure of the water and enables a tight joint to be maintained between the faucet and the tube.

By reason of the dish washer being a hand-held device, it is important that the hands be protected from the heat of the hot water passing therethrough. To protect the hands of the operator from such discomfort, the device is provided with a tubular handle 33, which tube surrounds the flexible tube 15 adjacent to the inlet end of the casing. The tubular handle 33 is of two diameters, the smaller diameter being cemented to the tube 15 at its point of connection with the inlet tube 14 of the cap 11, and the enlarged portion of the handle being spaced away from the tube 15. This arrangement leaves an air space between the handle and the tube that protects the operator's hands from the heat of the hot water passing through said tube.

Obviously, the construction hereinbefore described admits of considerable variation without departing from the invention.

What we claim is:

1. A fluid discharging device comprising a casing having an inlet at one end and a tapering nozzle portion and a plurality of discharge apertures at its opposite end, a foraminous soap container rotatably supported within said casing, a cover for said container, said cover having a plurality of flanged openings formed therein, whereby liquid entering said casing passes through

said openings into said container, said openings being positioned with relation to the inlet of said casing so that the fluid acts against the flanged portions of said openings to rotate said container and a V-shaped plate disposed in said nozzle portion to rotatably support said container.

2. A fluid discharging device comprising a casing having an inlet at one end and a discharge aperture at its opposite end, a foraminous soap container rotatably supported within said casing, and a cover for said container, said cover having a plurality of upwardly flanged elongated openings formed therein disposed transversely to the axis of said container and at right angles to each other, whereby liquid entering said casing acts against the flanged portions of said openings to rotate said container and passes into said container through said openings.

3. A fluid discharging device comprising a casing having an inlet at one end and a discharge aperture at its opposite end, a soap container rotatably supported within said casing, said container having foraminous side walls and having a plurality of flanged elongated openings formed in its top, whereby liquid entering said casing passes through said openings into said container, said openings being located adjacent to the inlet end of said casing and being disposed transversely to the axis thereof, and at substantially right angles to each other whereby the liquid acts against the flanged portions of said openings to rotate said container.

4. A fluid discharging device comprising a casing having an inlet at one end and a plurality of discharge apertures at its opposite end, a soap container rotatably supported within said casing, said container having foraminous side walls and a cone-shaped end disposed opposite to said inlet, the cone-shaped end of said container having a plurality of elongated openings formed therein and extending transversely to the axis of said casing and at substantially right angles to each other, the outside margins of said openings being provided with outwardly projecting flanges that con-

stitute vanes against which the liquid acts to impart a rotary motion to said container.

5. A fluid discharging device comprising a two-piece separable casing, one piece having an inlet tube projecting axially therefrom and adapted for connection with a faucet, the other piece having a tapering nozzle portion provided with a plurality of spray orifices, a foraminous soap container 55 rotatably mounted within said casing and having a central depression formed in its bottom surface, a cone-shaped cover for said container, said cover having a plurality of flanged openings formed therein disposed 60 transversely to the axis of said casing and at substantially right angles to each other, whereby liquid directed from said faucet against said cone-shaped cover acts against the flanged portions thereof to rotate said 65 container and passes through the openings therein into the container, and means for rotatably supporting said container in the second mentioned piece of said casing, said means comprising a V-shaped plate disposed 70 in the tapered nozzle portion of said piece and having a cross-head extending at right angles to said plate with its opposite ends abutting against the walls of said piece, said 75 cross-head having a pivot portion which cooperates with the depression in the bottom of said container to rotatably support the same.

6. A fluid discharging device comprising a two-piece separable casing, one piece having an inlet adapted for connection with a faucet, the other piece having a nozzle portion provided with a plurality of discharge orifices, a foraminous soap container located 80 within said casing, means on said container for imparting a rotary motion thereto by a stream of liquid directed thereagainst, and means for rotatably supporting said container, said means comprising a pivot plate 85 removably maintained within said casing, and adapted to be self-centering therewith and provided with a cross-head disposed at an angle with the body portion of the plate.

Signed at Jefferson City, Missouri, this 10th day of October, 1921.

HARRY W. THOMSON.

WILLIAM F. WINKELMANN.

Certificate of Correction.

It is hereby certified that in Letters Patent No. 1,491,212, granted April 22, 1924, upon the application of Harry W. Thomson and William F. Winkelmann, of Jefferson City, Missouri, for an improvement in "Fluid-Discharging Devices," an error appears in the printed specification requiring correction as follows: Page 2, line 42, strike out the words "container. The apex of the cone-shaped" and insert the same to follow after line 44; and that the said Letters Patent should be read with this correction therein that the same may conform to the record of the case in the Patent Office.

Signed and sealed this 27th day of May, A. D. 1924.
